UNITED STATES PATENT OFFICE.

IGNATZ J. LUDWIKOWSKI, OF STEVENS POINT, WISCONSIN.

COMBINATION IRONING BOARD AND STEPLADDER.

Application filed April 5, 1923. Serial No. 630,164.

This invention is a combination ironing board and step ladder, and the object is to provide a simple, efficient and practical combination of this kind.

5 In the drawing—

Figure 1 is a perspective view of the device folded together;

Figure 2 is a perspective view of the device set up for use as a step ladder;

10 Figure 3 is a side elevation of the device opened and set up for use as an ironing board.

The device consists of the combination of an ironing board 1, having its pointed or 15 tapered end 2 hinged at 3 to the narrowed or upper end of a step ladder 4. The said step ladder has an ironing board leg-frame 5 pivoted outwardly to it at the medial points 6, so that the said frame 5 may be 20 turned or folded down close along the side rails of the ladder when the device is to function as a ladder and not as an ironing board. A cross-slat 7 is fastened to the under side of the ironing board to act as a 25 stop for the inner end 8 of the leg-frame 5 when the latter is opened out to serve as a support for the device when it is used as an ironing board. A U-shaped link 9 has its free ends pivotally connected at 10 to 30 the free end of the ironing board, while the loop portion 11 is adapted to engage hooks 12 mounted on the lower ends of the side rails of the ladder 4, and so help support the device when used either as a ladder or 35 as an ironing board.

The operation and use of the device is obvious.

While I have herein described a certain specific manner and method of constructing and assembling the elements of my invention, it is understood I may vary from same in minor details, not departing from the spirit of my invention, as defined in the appended claim.

45 I claim:

A device of the kind described, comprising an ironing board and a step ladder, the said ironing board having a tapered end whereat it is hinged to the upper end of the step ladder and having a medial stop 50 upon its under side; an ironing board leg frame pivoted outwardly at medial points upon the step ladder, so that the said frame may be folded down close along the side rails of the ladder or may be opened out 55 with an end bearing against the said medial stop of the under side of the ironing board as a support for the ironing board; hooks upon the lower ends of the side rails of the ladder; a U-shaped link having its free ends 60 pivotally connected to the under side of the free end of the ironing board with its loop portion adapted to engage the said hooks at the lower ends of the side rails of the ladder whereby the said link is adapted to 65 serve as a foldable auxiliary support for the device when in use as an ironing board.
